(57) **CLAIM**

The ornamental design for a hanger adapter, as shown and described.

DESCRIPTION

FIG. 1 is a front perspective view of a first embodiment of a hanger adapter shown in environmental use;
FIG. 2 is a front perspective view of the hanger adapter of FIG. 1;

FIG. 3 is a front elevation view thereof, the rear elevation view being an identical image thereof;
FIG. 4 is a left side elevation view thereof, the right side elevation view being an identical image thereof;
FIG. 5 is a top plan view thereof;
FIG. 6 is a bottom plan thereof;

FIG. 7 is a front perspective view of a second embodiment of a hanger adapter shown in environmental use;
FIG. 8 is a front perspective view of the hanger adapter of FIG. 7;

FIG. 9 is a front elevation view thereof, the rear elevation view being an identical image thereof;
FIG. 10 is a left side elevation view thereof, the right side elevation view being an identical image thereof;
FIG. 11 is a top plan view thereof; and,
FIG. 12 is a bottom plan thereof.

The broken lines shown in the drawings depict a clothes hanger that forms no part of the claimed invention.

1 Claim, 6 Drawing Sheets
